UNITED STATES PATENT OFFICE.

EMMET S. LONG, OF VERNON, CALIFORNIA, ASSIGNOR TO THE LONG TURNER CORPORATION, OF VERNON, CALIFORNIA, A CORPORATION OF CALIFORNIA.

TELEPHONE.

Application filed June 7, 1924. Serial No. 718,495.

This invention relates to telephones and more especially to the construction of the transmitter, and an object of the invention, in general, is to produce a more serviceable instrument than those at present in use.

An important object of the invention is to increase the clarity of the sounds transmitted over the telephone.

An object, that is incident to the construction that is relied upon to effect the object last above noted and that, in another way, is quite as important, is to minimize breakage of the mouthpiece. The importance of this will be readily appreciated when it is borne in mind that the cost of replacing broken mouthpieces amounts, in the United States alone, to very large sums of money.

Another important object is to provide a construction of transmitter that, when used on a desk phone, will greatly reduce the maintenance cost of such phone.

Other objects and advantages will appear in the subjoined detailed description.

The following drawings illustrate the invention:

Fig. 1 is a front view of a telephone transmitter constructed in accordance with the provisions of this invention.

Fig. 2 is a rear view of the transmitter shown in Fig. 1.

Fig. 3 is an elevation, mainly in section on the line indicated by 3—3 Fig. 2.

Fig. 4 is a fragmental sectional detail on the line indicated by 4—4, Fig. 2.

Fig. 5 is a rear face view of the metal insert of the transmitter.

Fig. 6 is an end view of the metal insert of the mouth piece of the transmitter.

Fig. 7 is a side elevation of Fig. 6.

Fig. 8 is a rear face view of the bridge of the transmitter.

Fig. 9 is a sectional elevation on the line indicated by 9—9, Fig. 8.

Referring to the construction of the transmitter, disclosed in Figs. 1 to 9, inclusive, there is provided a transmitter face insert 15 of metal and of circular construction, provided at diametrically opposite points with rearwardly projecting lugs 16 which may be of integral construction with the member 15. The outer surface of the insert 15 is provided with a soft non-metallic covering 17 of sound-deadening material such as, for example, soft rubber which is molded in place upon the insert. Preferably

the insert 15 is provided with a number of perforations 18 through which the covering 17 projects so as to more firmly hold the covering in place. The same covering material forms an annular flange 19 which projects from the rear face of the insert 15 and covers the inner faces of the lugs 16 as clearly shown in Fig. 3.

The flange 19 is provided interiorly with an annular shoulder 20 against which seats a transmitter diaphragm 21 that is thus separated from the lugs 16 by the flange 19 of soft sound-deadening material.

Secured by screws 22 to the lugs 16 is a bridge 23 of firm, non-metallic material such as, for example, a phenol condensation product. The bridge 23 carries the resistance unit or, as it is generally termed, "button", indicated in general by the character 24. The "button" 24 need not be described in detail as its construction is well understood by those versed in this art.

The insert 15 is provided with a central opening 25 to admit sound, the wall of said opening being threaded as indicated at 26 to engage the screw threads 27 of an annular mouthpiece insert 28 of metal. The insert 28 is provided in its interior with a wall 29 having perforations 30. When the insert 28 is screwed into the insert 15, a portion thereof projects beyond the outer face of said insert 15 and said projecting portion is embedded in a soft sound-deadening funnel-form covering 31, only the extreme inner end of the covering 31 engaging the insert 28 so that, in the main, the mouthpiece is soft and flexible. To insure bonding between the insert 28 and covering 31, the insert 28 may be provided with perforations 32 through which the covering 31 extends. The covering 31 also preferably extends along both faces of the wall 29 so as to cover said faces. To further insure bonding between the covering 31 and insert 28, said insert is provided on its outer face with an annular flange 281 knurled on its outer face, as indicated at 282. To insure against sweating of the diaphragm and to prevent damping of the diaphragm's vibration, vents 283 are provided in the mouthpiece and said vents extend through the covering 31 adjacent to the screw threads 27 and through said screw threads to the inner end of the insert 28.

In order that the transmitter face may be

secured to the transmitter shell, not shown, I provide curved metal inserts 33 in the flange 19, the ends of said inserts 33 being spaced from the lugs 16 and the material 5 of the flange 19 filling the spaces. Slots 34 are cut in the flange 19 at intervals to expose the inserts 33 and at these slots the inserts 33 are provided with threaded holes 35 to receive the screws that fasten the transmitter face to the transmitter shell, not shown.

When the transmitter is in use, any sounds extraneous to the mouthpiece, will strike the soft coverings 17, 31 and be absorbed there- 15 by instead of being transmitted to the diaphragm, as occurs in the transmitters of prior construction, even though, in the prior transmitters, a thin piece of fabric is placed between the diaphragm and its 20 seat. Such thin piece of fabric affords very little protection to the diaphragm against receiving extraneous sounds through the transmitter walls.

By making the bridge 23 of non-metallic 25 material, I eliminate many pieces of electrical insulation necessary when the bridge is made of metal.

If the transmitter be that of a desk phone and the phone is knocked off of the deck or 30 other support, the mouthpiece will yield when it strikes the floor or other object and will not break as is a common occurrence with those at present in use. Even though my new mouthpiece be used as a 35 substitute for the mouthpiece of the old breakable type of transmitter, it will be apparent that the resiliency of said mouthpiece will ordinarily amply protect the transmitter against injury in case of the 40 telephone falling upon the floor or being accidentally struck. Also my new mouthpiece, when used on the old type of transmitter face in lieu of the old mouthpiece, will to some degree clarify the transmission of 45 sound over the telephone, since those external sounds that ordinarily are received by the mouthpiece and transmitted through the face to the diaphragm, will be absorbed by the mouthpiece. It is to be noted that any 50 vibrations affecting the telephone shank and transmitter shell cannot reach the transmitter face because of the spacing of the screw-receiving member 35 from the face insert 15 and lugs 16.

It will be apparent from the foregoing 55 description of the invention that my new construction has several advantages that the prior constructions do not have. The coverings 17 and 31 absorb extraneous noises 60 and insure against breakages; the flange 19 prevents vibrations being transmitted from

the transmitter face to the diaphragm and the transmission of vibrations from the transmitter shell to the transmitter face and the bridge 23 eliminates the use of many 65 pieces of insulation formerly necessary.

Of great importance is the fact that the mounting of the members 33 independent of the lugs 16 prevents vibrations being 70 transmitted from the transmitter face and from the transmitter shell through the face to the bridge and thence to the extremely sensitive button.

I claim:—

1. A telephone transmitter comprising a 75 metal insert having lugs and a sound-receiving opening, a rigid non-metallic bridge secured to the lugs, a soft sound-deadening covering for the outer face of the insert, a soft sound-deadening annular flange on the 80 inner face of the insert covering the inner faces of the lugs and having an annular shoulder, a diaphragm seated against said shoulder and positioned to receive sound through the opening, and a "button" 85 mounted on the bridge in operative relation with the diaphragm.

2. A telephone transmitter comprising a metal insert having lugs and a sound-receiving opening, a rigid non-metallic 90 bridge secured to the lugs, a soft sound-deadening covering for the outer face of the insert, a soft sound-deadening annular flange on the inner face of the insert covering the inner faces of the lugs and having 95 an annular shoulder, a diaphragm seated against said shoulder and positioned to receive sound through the opening, and a "button" mounted on the bridge in operative relation with the diaphragm. 100

3. A telephone transmitter comprising a metal insert having lugs and a sound-receiving opening, a rigid non-metallic bridge secured to the lugs, a soft sound-deadening covering for the outer face of the insert, a soft sound-deadening annular flange on the 105 inner face of the insert covering the inner faces of the lugs and having an annular shoulder, a diaphragm seated against said shoulder and positioned to receive sound 110 through the opening, a "button" mounted on the bridge in operative relation with the diaphragm, and curved metal inserts 115 partly imbedded in the flange and having their ends spaced from the lugs, said curved inserts having threaded holes to receive screws for securing the curved inserts to a transmitter shell.

Signed at Los Angeles, California, this 26th day of May, 1924.

EMMET S. LONG.
